UNITED STATES PATENT OFFICE.

JOHN AUSTIN, OF GENEVA, OHIO.

PIPE.

1,388,158.

Specification of Letters Patent. Patented Aug. 23, 1921.

Application filed September 16, 1919. Serial No. 324,097.

To all whom it may concern:

Be it known that I, JOHN AUSTIN, a citizen of the United States, residing at Geneva, in the county of Ashtabula and State of 5 Ohio, have invented a new and useful Pipe, of which the following is a specification.

This invention relates to tobacco pipes and one of its objects is to provide a device of this character having means whereby hot 10 air accumulating at the point of connection between the bottom of the bowl and the passage in the stem may escape through the wall of the bowl.

A further object is to provide a device of 15 this character having means for regulating the flow of air into the stem.

With the foregoing and other objects in view which will appear as the description proceeds, the invention consists of certain 20 novel details of construction and combinations of parts which will be hereinafter more fully described and pointed out in the claim, it being understood that various changes may be made in the construction and arrangement of the parts without departing 25 from the spirit or sacrificing any of the advantages of the invention as set forth in the appended claim.

In the accompanying drawing the preferred forms of the invention have been 30 shown.

In said drawings—

Figure 1 is a view partly in side elevation and partly in section of a pipe embodying 35 the present improvements.

Fig. 2 is a plan view of the bowl thereof.

Fig. 3 is a plan view, partly in section, of the bowl having a modified form of damper.

40 Referring to the figures by characters of reference, 1 designates the stem and 2 the bowl of a tobacco pipe. A passage 3 is formed in the wall of the bowl and extends from the upper edge thereof to the passage 45 4 formed in the stem, the two passages meeting at a point close to the interior of the bowl.

Formed in the wall of the bowl near the upper edge thereof and intersecting the passage 50 5 is a slot in which a damper plate 6 is pivotally mounted, as at 7. One end of

the plate is adapted, when the plate is in housed position, to close the passage 3. An ear 8 projects from the outer edge of the damper and has its opposed edges recessed 55 to form points 9. Either of the recesses is adapted to receive the edge of a fingernail whereby the damper can be swung readily out of the recess to open the passage 3.

Instead of providing the particular damper described, a damper in the form of a strip 10 can be pivotally mounted on the edge of the bowl, as shown at 11 in Fig. 3.

It will be understood that while the pipe is in use a partial vacuum will be produced 65 in the passage 3. Consequently the atmospheric pressure will cause fresh air to flow into said passage with the result that the smoking of the pipe will be rendered more enjoyable and the bowl will be kept dry and 70 nearly odorless.

While the dampers or cut-offs 6 and 10 can be utilized for regulating the flow of 75 fresh air into the passage 3, they are useful as means for preventing dirt and other foreign substances from entering the passage 3 and choking it.

What is claimed is:—

A tobacco pipe including a stem having a passage therein, a bowl opening into the 80 passage and having an air passage in the wall thereof opening at one end into the passage in the stem and at its other end through the top of the bowl, there being a slot extending partly through the wall of 85 the bowl and intersecting the passage in said bowl, a damper pivotally mounted in the slot and normally filling the same, said damper being movable to open or close the passage in the bowl, and a projection on the 90 narrow portion of the damper and extending beyond the wall of the bowl, said projection having opposed finger nail receiving recesses.

In testimony that I claim the foregoing 95 as my own, I have hereto affixed my signature in the presence of two witnesses.

JOHN AUSTIN.
